UNITED STATES PATENT OFFICE

2,517,056

THERMOSTATIC MIXER

René Trubert, Viroflay, France

Application October 23, 1946, Serial No. 705,223
In France June 2, 1942Section 1, Public Law 690, August 8, 1946
Patent expires June 2, 1962

5 Claims. (Cl. 236—12)

1

The invention relates to thermostatic mixers of the type in which a bimetal strip is so arranged as to permit to keep at a constantly even temperature the liquid furnished by the apparatus, while the latter is fed by means of two inlets of hot and cold water respectively.

A mixer of that type has already been described in the U. S. Patent No. 1,943,705 of January 16, 1934, of the same inventor. The chief aim of the present invention is to improve the construction of the said mixer as regards cost price, facility of mounting or dismounting, robustness of the whole, and also precision and dependability in working.

The invention is essentially characterized in that the bimetal strip which regulates the proportion of the mixture in cooperation with two nozzles controlling the two inlet pipe diaphragm valves, now actuates a rocking distributor mounted inside a housing fitting with said nozzles, the said bimetal strip being supported by a small flexible strip the position of which adjusted by means of a screw-threaded stem actuated by an external hand-operated knob.

Various other features of the invention will be set forth thereafter with reference to the accompanying drawing which shows by way of example a constructional form of the invention and also a modification in the diaphragm valves.

Figure 1 is a longitudinal sectional view of the apparatus.

Figure 2 is a transverse sectional view.

Figure 3 shows details of the distributor actuated by the bimetal strip.

Figures 4 and 5 show sectional views of a diaphragm valve according to the invention, in two different positions of the said diaphragms.

The apparatus as shown by Figures 1 and 2 comprises substantially a body 1 provided with screw-threaded portions 2, 3 and 4 which receive pipe connections. The body 1 is further provided with an aperture 5 (Figure 2) utilised for inspection of members located inside. Inside the body 1 is fitted a bimetal strip 6 actuating the distributor of hot and cold liquids.

According to a feature of the invention the said bimetal strip is connected with the support 7 thereof by means of a small flexible strip 8. A member 9 fitted on the bimetal strip cooperates with the temperature adjustment device. This structure allows an insertion of the bimetallic strip 6 and the support 7 thereof into the body through the aperture of the threaded portion 2. The drawing shows a form where the small flexible strip 8 also acts as a drawback spring, but

2

the said small strip, connected both with the support 7 and the bimetal strip 6, could serve only as a flexible support, a separate drawback spring being, in this case, provided for.

Another feature of the temperature adjustment device, is that the same comprises a stem 10 with a threaded portion 11. Said threaded portion may be more or less quick-pitched according to the scale of temperatures required, and will engage the inside thread of the body threaded portion 2, the pitch of which being, naturally, in accordance. The other end of the stem 10 is tapered and the position of the hand-operated knob 13 can be set instantaneously with respect to the angular position of the stem 10, by loosening the screw 14, and placing the index 15 in front of a corresponding figure of the dial 16, no dismounting being needed.

As may be seen in Figure 2, the stem 10, when rotated, actuates the member 9 of the bimetal strip 6, thus pressing the drawback spring, and operates the necessary adjustment.

The distributor, proper of hot and cold water comprises a member 17 shown in a larger scale in Figure 3, rocking about a point 18, and actuated by the end of the bimetal strip 6. This member is provided with recesses 19 and 20 movable in front of the nozzles 21 and 22 when the bimetal strip rocks the member 17. These motions uncover more or less the nozzles 21 and 22 or else let them both slightly open according to the temperature of the bimetal strip, in relation with the heat of the required mixture which has been regulated by means of the hand knob 13. The said member 17 is mounted inside a small housing 23 of general cylindrical shape having a transverse central aperture in which rocks the member 17, whereas said transverse aperture communicates with said nozzles 21 and 22. The edges 24 of this transverse aperture act as abutments to limitate in both directions the motion of member 17.

The nozzles 21—22 cooperate respectively with the diaphragms 25—26 which regulate the inflow of hot and cold water by opening or closing the water inlets 29—30; when a water inlet 29—30 is opened, the water flows through lateral apertures 31—32 upon which the diaphragm is brought to bear when in its closing position. Each diaphragm is provided centrally with a small orifice, the object of same being to create behind said diaphragm a back pressure necessary for the working thereof, as will be explained thereafter.

Filters 33—34 supporting the guide links of non-return valves 35—36 have been provided in

front of diaphragms 25-26. In Figure 1, the non-return valve 33 is shown open, and the valve 35 closed. It is to be noted that such device can be taken off and replaced easily by unscrewing the pipe connections 37 and 38. Spikes, or lugs, project from one of the valves, the cap thereof and the distributor.

It is also to be noted that the device is likewise provided with connections 39 and 40, to be welded, or connected by a screw connection to the pipe connections 37 and 38, respectively, thus permitting the apparatus to be taken apart without moving the feeding pipes.

Between the pipe connections 37-38 and the members 41-42 supporting the diaphragms 25-26 is fitted a gasket 43-44 operating both ways, especially in a direction parallel to the axis of said pipe connections and then radially, thus ensuring water-tightness between members 37-38 and 41-42, and besides, between these two members 41-42 and the threaded portions 3 and 4 of the body 1. The surfaces of members 37-38 and 41-42, contacting the water-tight facings 43-44 are, owing to this, slightly tapered. The pipe connections 37 and 38 on engaging the threaded portions 3 and 4 bear upon the facings 43-44 pressing same in the direction of the axis and also pushing them away radially. Besides, according to the invention, the bimetal strip 6, which is constantly flooded, may be protected against corrosion with a cover of such material as varnish, rubber or the like, this further to the usual metal protection.

The manner of operation of the apparatus is similar to what has been described in the above-mentioned U. S. patent. When the temperature of the mixture grows higher or lower, the bimetal strip causes the distributor to rock. If the mixture is too hot, for instance, the distributor will move in the way which will lessen the outflow through the hot water nozzle and the back pressure thus created behind the hot water inlet diaphragm will cause the closing of same, whilst the other diaphragm, which will have been relieved of its back pressure by the opening of the other nozzle, will then allow cold water to flow in. When the inflow of cold water has decreased the temperature of the bimetal strip to such an extent that the mixture would become too cold, a reverse rocking motion of the said bimetal strip takes place, thus closing the cold water inlet and opening the hot water inlet. These non-stop rocking motions will maintain constantly the heat of the mixture at the same value.

The diaphragms 25-26 actuated by the back pressure of the inflow which they control, may comprise according to the invention a central circular rigid portion and outwardly an annular extensible portion.

Ordinary diaphragms, such as for instance those in which flexibility is provided for by means of concentric corrugations, would not be suitable as the back pressure would possibly cause permanent deformations. Besides, the water pressure bears upon an equal area on both sides, and would not have sufficient power for closing.

To obtain such necessary power, the invention provides for a constructional form in which the diaphragm is made of natural or synthetic rubber, or like material which may be reinforced by a linen. A rigid metal disc is inserted centrally, and in the remaining annular outward portion are two or a plurality of folds so arranged as to permit the diaphragm to be easily depressed in one direction whilst strongly resisting the water

pressure from the other direction. Such a form is illustrated by Figures 4 and 5 which show the diaphragm 51 with the inner disc 52, the closing side 53, the outer facing 54, the closing fold 55, the opening fold 56, the orifice 57 (similar to pipes 27-28), the spring 58. There can also be seen the valve 59 comprising the inlet pipe 60, the seat 61, the perforated shoulder 62, the edge 63, the cap 64, the closing ring 65 and the aperture 66 (similar to apertures 21-22).

The manner of operation of the diaphragm is as follows:

In Figure 4, the aperture 66 is closed; the liquid flowing into the pipe 60 passes through the orifice 57 and bears with equal strength upon the central portion of the side 53 corresponding to the seat 61 and upon the area of the facing 54 corresponding to the disc 52. The diameter of the disc being larger than that of the seat, the diaphragm 51 is pressed upon the seat in correspondence with the pressure power, thus preventing the passing of the water. Outside the disc area, the outward annular flexible portion of the diaphragm, comprising folds 55 and 56, bears against the perforated shoulder 62, the pressure having a tendency to tighten the folds; however said folds are deep enough to have a sufficient rigidity which will permit the diaphragm to bear against the shoulder without substantial deformation.

In Figure 5, which shows the diaphragm in its open position, the aperture 66 has been opened. Accordingly, the liquid passing through the orifice 57 will no longer be pressed under the cap 64 and the water pressure into the inlet pipe 60 will be sufficient to raise the diaphragm from the seat 61, thus providing an escape through which the water will flow in the direction of the arrows.

The spring 58 has no other object than to prevent deformation of the diaphragm when the valve is not in operation.

The above description has only been set forth by way of example, and obviously, modified constructional forms would still be within the scope of the invention. For instance, it will be observed that the closing portion of the diaphragm may have any other shape such as frusto conical or hemi-spherical, or could be mounted in a different manner, e. g. the diaphragm could be squeezed between the valve and the cap, by nuts or other means.

I claim:

1. A thermostatic mixer for liquids comprising a hot liquid inlet, a cold liquid inlet, an outlet for the mixed liquid, two diaphragm valves, each for controlling one of said inlets, a seat for the front face of each said valve, at least one aperture in said seat communicating with the corresponding inlet, at least one aperture in said seat communicating with said outlet, a back pressure chamber on the rear side on each said valve, a small passage through each of said valves between inlet and back pressure chamber, a stationary housing between the two back pressure chambers, a transverse aperture in said housing in communication with the outlet, two nozzles in the lateral faces of said housing giving passage between said two back pressure chambers and the transverse aperture, a rocking distributor movable in the transverse aperture of said housing between said nozzles, a bimetal strip connected with said distributor and carried by a spring strip and means for adjusting said bimetal strip comprising an external rotatable hand operated knob and a screw-threaded stem connected to said knob.

2. A thermostatic mixer as claimed in claim 1, in which the stem of the adjusting means is tapered at its outward end to receive the hand operated knob, the other end being screw threaded with a pitch in accordance with the required scale of temperature with which the apparatus is to be used.

3. A thermostatic mixer as claimed in claim 1, in which the edges of said transverse apertures of the distributor housing comprise abutments for limitating in both directions the movement of the rocking distributor, said distributor having recesses which move in front of said nozzles to adjust the back pressures operating the diaphragm valves.

4. A thermostatic mixer as claimed in claim 1, in which the seat of each diaphragm valve comprises a central aperture communicating with the inlet whereas the central part of said valve in front of said aperture comprises a first external elastic layer on its front side, a second external elastic layer of lesser thickness on its rear side and a rigid internal disc inserted between said elastic layers and having a larger diameter than said central aperture.

5. A thermostatic mixer as claimed in claim 1, in which the seat of each diaphragm valve comprises a central aperture in communication with

said liquid inlet and other apertures which are in communication with said outlet and are arranged around said central aperture, whereas the diaphragm valve comprises in its peripheral portion, in front of said other apertures, at least two folds applied one on the other in the closed position of the valve and adapted to open themselves when the valve opens, for the purpose of giving to said valve a sufficient flexibility.
